ABCDEFGHIJKLMN OPQRSTUVWXYZ

abcdefghijklmnopqrstuvwxyz

01234567890

A vertical sequence of eight arrows pointing in various directions: up, down, left, and right. The arrows are arranged in a pattern that suggests a search or a path through a grid.